AUGUSTINUS EDWARD JONSSON, OF LIDINGO, SWEDEN

DRYING APPARATUS

Application filed February 14, 1929, Serial No. 340,000, and in Sweden February 15, 1928.

The present invention relates to an improvement in drying apparatus of the type described and claimed in my copending application Serial No. 339,999, and which comprises a rotating or oscillating cylinder, provided with heating-bodies or units adapted to heat and distribute the material to be dried. The principal object of the invention is to provide a drying apparatus of this character in which the heating units are provided with or have formed thereon ribs or projections spaced at suitable distances from each other, the material being dried resting against said ribs or projections. By this construction said material will be prevented from contacting with the heating-bodies too closely, thus avoiding too rapid heat absorption.

The heating-bodies or units may consist of heating-casings or jackets, disposed on the cylinder and/or the ends thereof, but they may also consist of special heating-units extending into the cylinder. These two alternatives may be used simultaneously. According to a further embodiment of the invention, the ribs or projections may be constructed of a material which is of low heat conductivity or possessing heat-insulating properties. Again, the ribs or projections may have only their faces, which contact the material in question, provided or coated with a material of low conductivity or heat-insulating properties. These ribs or projections serve not only to prevent the material from making too direct a thermal contact with the heating-bodies, but also to facilitate the removal of the vapors expelled from said material, for the reason that the ribs or projections form channels by means of which said vapors may more easily escape than through the mass of the material being dried.

In the drawings accompanying this specification,

Fig. 1 is a fragmentary longitudinal sectional view through an apparatus embodying the features of the present invention;

Fig. 2 is a cross-section taken on the line II-II in Fig. 1;

Fig. 3 is a sectional view taken on the line III-III in Fig. 2;

Fig. 4 is a view similar to Fig. 2, illustrating a modified form of the invention; and

Fig. 5 is a sectional view taken on the line V-V in Fig. 4.

Referring first to Figs. 1-3, 1 designates a drying-cylinder, which is mounted to rotate in any suitable manner and may be given a rotating or an oscillatory movement by means of a suitable driving-device, known per se. The side and end walls of the cylinder are preferably of double-walled construction thereby to form heating jackets 5. Within the cylinder are disposed a plurality of hollow heating units 4, said units communicating by means of pipes with the jackets 5. A heating-fluid is conveyed to the heating units 4 by a pipe, not shown, and after having passed through and been cooled in the several heating units of the drying-cylinder, it is allowed to escape through a suitable outlet. In order to obtain a rapid and efficient drying operation, a vacuum may be created within the cylinder by means of a suitable vacuum pump, in a manner known per se. To carry and guide the inner free ends of the heating units 4, extending inwards, supports or columns 15 are placed diametrically within the cylinder, said columns being provided with flanges 16 upon which the ends of the heating units rest. The heating units 4, and, if desired, also the inner surface of the cylinder wall, as well as the end wall are provided with ribs or projections 6, which form supports for the material being dried so as to prevent too strong a heating of said material. Said ribs may for this purpose be made integral with the heating units and the jackets, or they may be attached to them in any suitable manner, for instance by welding or riveting, in which case the ribs may consist of a material having a low heat conductivity or having heat-insulating properties in order to prevent too strong a heating of the goods being dried.

According to the embodiment shown in Figs. 4 and 5, the ribs are partially integral with the heating units and the outer portions 20 thereof are of a material of low heat conductivity. To permit the portions 20 to be securely attached, the ribs 6 may be

formed, for instance with a pair of thin side flanges 21, between which the portions 20 may be secured, as shown in Fig. 5.

Having thus described my invention, what

5 I claim is:—

1. A drying apparatus comprising in combination with a rotatable cylinder, a plurality of hollow flat heating shelves extending through the whole length of the cylinder and 10 grouped in parallel on both sides of a free space extending diametrically through the axis of the cylinder perpendicular to the plane of the shelves, each of said shelves extending from the circumference of the cylinder 15 to said diametrical free space, said space communicating with the feeding and discharging openings in the wall of the cylinder, said flat shelves having a plurality of ribs disposed in embracing relation to the exterior 20 of the heating shelves and extending perpendicular to the axis of the cylinder thereby to prevent the material being dried from coming into direct contact with the walls of the flat shelves.

25 2. A drying apparatus comprising in combination with a rotatable cylinder, a plurality of hollow plane heating shelves extending through the whole length of the cylinder and grouped in parallel on both sides 30 of a space extending in a diametrical plane perpendicular to the plane of the shelves and communicating with the feeding and discharging opening in the wall of the cylinder, said shelves having a plurality of ribs disposed 35 in embracing relation to the exterior of the plane heating shelves and extending perpendicular to the axis of the cylinder thereby to prevent the material being dried from coming into direct contact with the walls of the shelves, said ribs being formed 40 of a material of low heat conductivity.

3. A drying apparatus comprising in combination with a rotatable cylinder, a plurality of hollow plane heating shelves extending 45 through the whole length of the cylinder and grouped in parallel on both sides of a space extending in a diametrical plane perpendicular to the plane of the shelves and communicating with the feeding and discharging opening in the wall of the cylinder, said shelves having a plurality of ribs disposed 50 in embracing relation to the exterior of the plane heating shelves and extending perpendicular to the axis of the cylinder thereby to prevent the material being dried from coming into direct contact with the walls of the shelves, said ribs being formed 55 of a heat-insulating material.

4. A drying apparatus comprising in combination with a rotatable cylinder, a plurality of hollow plane heating shelves extending through the whole length of the cylinder and grouped in parallel on both sides 60 of a space extending in a diametrical plane perpendicular to the plane of the shelves and

communicating with the feeding and discharging opening in the wall of the cylinder, said shelves having a plurality of ribs disposed in embracing relation to the exterior of the plane heating shelves and extending 70 perpendicular to the axis of the cylinder thereby to prevent the material being dried from coming into direct contact with the walls of the shelves, those surfaces of the ribs which are in contact with the material to be dried being coated with a material having a low heat conductivity.

5. A drying apparatus comprising in combination with a rotatable cylinder, a plurality of hollow plane heating shelves extending through the whole length of the cylinder and grouped in parallel on both sides of a space extending in a diametrical plane perpendicular to the plane of the shelves and communicating with the feeding and discharging opening in the wall of the cylinder, said shelves having a plurality of ribs disposed in embracing relation to the exterior of the plane heating shelves and extending 75 perpendicular to the axis of the cylinder thereby to prevent the material being dried from coming into direct contact with the walls of the shelves, those surfaces of the ribs which are in contact with the material to be dried being coated with a heat-insulating material.
